Inventor.
David Allen,
By his Attorney,
John C. Lennox.

UNITED STATES PATENT OFFICE.

DAVID ALLEN, OF ALBANY, NEW YORK.

DESIGN FOR A CIGAR-BOX.

SPECIFICATION forming part of Design No. 17,046, dated January 4, 1887.

Application filed July 15, 1886. Serial No. 208,142. Term of patent 3½ years.

To all whom it may concern.

Be it known that I, DAVID ALLEN, a citizen of the United States, residing at Albany, in the county of Albany and State of New York, have invented certain new and useful Improvements in a Design for Cigar-Boxes; and I do hereby declare the following to be a full, clear, and exact description of the invention, such as will enable others skilled in the art to which it appertains to make and use the same.

The leading feature of my design consists in a raised panel upon the inside of the cigar-box cover and of contrasting shade to said cover, and a raised ornamentation upon said panel and of contrasting shade to the latter.

The accompanying drawing illustrates a perspective view of a cigar-box illustrating my design.

A indicates the cigar-box proper, and b the cover. Upon the inner side of the cover is attached the strip or panel c, of contrasting

shade to that of the inside of the cover, and raised above the surface of the latter, as indicated. Upon this panel is attached a raised ornamentation, as shown, said ornamentation being of contrasting shade to the panel to which it is attached. 25

Having thus described my design, what I claim, and desire to secure by Letters Patent for the same, is—

The design for a cigar-box herein shown and described, consisting of a box provided with a cover having a raised panel upon the inside of said cover and of contrasting shade thereto, and a raised ornamentation upon said panel and of contrasting shade to the latter. 35

In testimony whereof I affix my signature in presence of two witnesses.

DAVID ALLEN.
